THREAD GUIDE FOR WINDING MACHINES

Abraham Amel, Pawtucket, R. I.

Application September 20, 1933, Serial No. 690,189

2 Claims. (Cl. 242—157)

This invention relates to an improved thread guide for winding machines adapted for use generally in connection with the various types of winding machines employed for winding thread upon bobbins, cops, quills and the like from a skein or spool.

One object of the invention is the provision of a thread guide of the character described adapted to eliminate the formation of narrow 10 cuts in the thread guiding element resulting from constant wear and which frequently cause breakage of the thread when an enlarged portion of the thread is drawn into one of these narrow cuts.

Another object of the invention is the provision of a thread guide having a contact member 15 mounted for rotation as the thread is drawn thereover and provided with a transversely curved groove for receiving and guiding the thread thereby preventing excessive wear at any one portion of the contact surface.

A further object of the invention is the provision of a simple and efficient means for supporting the rotatable contact member or guide pulley in such a manner as to permit the removal and replacement of the guide pulley readily when desired as well as means for preventing excessive wear between the pulley and supporting member.

Other objects and advantages of the invention relate to various improved details of construction and novel arrangements of the parts as will be more fully set forth in the detailed description to follow.

Referring to the drawing:—

Fig. 1 is a top plan view of a portion of a winding machine mechanism of a conventional type, illustrating the relative position of the thread guide members with relation to the skeins or 40 spools and the bobbins or cops to be wound,

Fig. 2 is a perspective view of one of the thread guide members removed from the guide rail,

Fig. 3 is a horizontal sectional view through the thread guide member, taken substantially 45 along the horizontal plane indicated by the line 3—3 of Fig. 2, and,

Fig. 4 is a perspective view of the guide pulley supporting shaft as seen when removed from the guide block.

In the embodiment of the invention illustrated herewith, 1 designates a reel shaft which may be provided with a plurality of reels 2, carrying skeins 3 of thread to be wound upon bobbins, cops, or the like after a manner well known in the art. 50 Supporting plates 5 are secured to suitable por-

tions of the main frame (not shown) of the machine and provide bearings for rotatably supporting spindles 6, each of which may be provided with a drive pulley 7, whereby each spindle may be rotated from a suitable source of power through a drive belt 8. A bobbin 10 is adapted to be mounted on each spindle 6 and rotated thereby through ratchet teeth 12 or by any other suitable means.

A longitudinally reciprocating guide rail 14 is located intermediate the reels 2 and bobbins 10, which may be reciprocated by an arm 15 from a portion of the drive mechanism after a manner well known in the art. The guide rail 14 may rest upon and be guided in its reciprocating movement by a stationary supporting beam 16, and may be provided upon its upper face with a groove 17 extending longitudinally of the guide rail and for a purpose which will be more fully set forth hereinafter.

The improved thread guides 20 are each adapted to be seated upon the guide rail 14 and suitably positioned thereon at a point between one of the skeins 3 and its corresponding bobbin 10. Each thread guide 20 comprises a body portion 21 which may be formed of wood, fibre, hard rubber, or other suitable material, and which has a base flange 22 adapted to fit within the groove 17 formed upon the upper face of the guide rail 14. Opposed recesses 23 may be formed 25 in the top surface of the body portion 21 of the thread guide to receive portions of holding clips 24 carried by or secured in the guide rail for holding each thread guide member firmly in position upon the guide rail. A transverse channel 25 is formed in the body portion of the thread guide 30 to receive a contact pulley or guide pulley 26, which is rotatably mounted on a shaft 27 and provided with a surface groove 28 for receiving and guiding the thread. The guide pulley 26 is 40 preferably provided with a bushing 30 formed from wood, fibre, hard rubber, or other suitable material to reduce the wear upon the bearing shaft 27.

The shaft 27 may be formed to extend partially or entirely through the body portion 21 of the thread guide, dependent upon the extent of the aligned openings 31 formed in the opposed end portions of the thread guide member, and may be held in position therein by having the end portion 32 thereof bent to provide a resilient clip 33 shaped to spring into gripping engagement with one of the inclined faces 34 of the body portion 21 of the thread guide, after the manner shown in Figs. 2 and 3 of the drawing.

As the bobbins 10 are rotated through the drive belts 8, a thread 35 is drawn from each skein 3 and wound upon each bobbin. Each thread passes over one of the rotatable guide pulleys 26 and is laid spirally upon the bobbin during the rotation thereof through reciprocation of the guide rail 14, the extent and speed of travel of the guide rail being proportioned to the speed of rotation and effective length of the bobbin employed.

10 While the mode of operation of the thread guides has been illustrated in connection with bobbins mounted in such a manner as to have their respective axes located in parallel relation with the direction of movement of the reciprocating guide rail, the thread guides are also adapted for use equally well with other forms of thread winders, such, for example, as those in which the axes of the bobbins or thread holders are located at right angles to the guide rail and 15 wherein the guide rail is given a reciprocating movement in a plane located above and in a direction parallel with the axes of the bobbins.

20 The provision of the rotatable contact or guide pulley 26 having a transversely curved groove formed in its exterior face to receive and guide a thread 35 from the skein to the bobbin provides a rolling contact surface for the thread at all 25 times and prevents the formation of narrow cuts or slits in the guide surface such as tend to cause 30 breakage of the thread when knots or enlargements occur in the thread.

The contact or guide pulley 26 may be provided with a non-metallic bushing 30 formed of any suitable material, as stated, or, if desired, the 35 entire pulley 26 may be formed from hard rubber, porcelain, "bakelite" or other suitable material such as may be appropriate to provide a rolling contact for a thread and which is relatively non-wearing upon the supporting shaft. The lateral 40 recess 25 formed for the reception of the rotatable pulley 26 in the body portion may be of less depth than that shown and may be in the form of a more or less shallow depression located in the top of the body portion of the guide member. The 45 upstanding end portions of the body member, of the form shown, serve to maintain the pulley 26

against axial movement relative to the supporting shaft and thus insure the thread being accurately laid upon the bobbin. Instead of forming the body member of a solid block other forms may be employed so long as means are provided for removably supporting the pulley shaft and for retaining the pulley in position axially of the shaft.

The provision of a wood, fibre or other similar form of bushing 30 within the thread guide pulley 26 serves to lessen the wear upon the shaft 27 incident to the friction between metal surfaces, thus lessening deterioration of the parts, and whenever the pulley 26 or shaft 27 become worn to such an extent as to make replacement desirable, either of these parts may be readily removed and replaced by the usual machine operator without requiring the services of a mechanic, by reason of the simplicity of the parts and the readiness with which the shaft 27 may be removed 20 from or replaced within the thread guide block.

What I claim is:—

1. A thread guiding means for winding machines comprising a body having upstanding portions spaced from each other and provided with 25 aligned recesses for the reception of a shaft member, a circumferentially grooved guide pulley located between said upstanding portions, a shaft member located within the aligned recesses and rotatably supporting said guide pulley, and resilient means carried by said shaft for frictionally 30 engaging a portion of said body to hold the shaft against accidental separation from the body.

2. A thread guide block having laterally inclined faces and provided with a transverse channel extending downwardly from the top of said guide block and having aligned shaft bearings formed therein and located upon opposite sides of the transverse channel, a shaft mounted in the shaft bearings and having an end portion extending outwardly radially of said shaft and adapted for clamping engagement with a portion of the thread block, and a guide pulley rotatably supported by said shaft within the transverse channel.

ABRAHAM AMEL.
